UNITED STATES PATENT OFFICE.

THOMAS ROMER WEYANT, OF BROOKLYN, NEW YORK, ASSIGNOR, BY
DIRECT AND MESNE ASSIGNMENTS, TO STANDARD FAN COMPANY,
OF NEW YORK, N. Y., A CORPORATION OF NEW YORK.

FAN.

SPECIFICATION forming part of Letters Patent No. 691,426, dated January 21, 1902.

Application filed October 30, 1900. Serial No. 34,885. (No model.)

To all whom it may concern:

Be it known that I, THOMAS ROMER WEYANT, a citizen of the United States, and a resident of Brooklyn, in the county of Kings and State of New York, have invented certain new and useful Improvements in Fans, of which the following is a specification.

My invention relates to fans and their attachments; and the principal object of said invention is to cause a better distribution and diffusion of the air-currents than can be obtained by the action of only the moving vanes or wings of the fan.

My invention consists generally in providing the fan with a movable support and connecting with said support one or more movable vanes or blades against which the currents of air supplied by the fan strike, and thereby cause the fan-support and fan to move, and also providing means for automatically changing the plane of said vane or vanes, whereby the currents of air will reverse the movement of the fan-support and fan, so that the currents of air will be moved in different directions.

My invention also consists in certain features and devices herein described.

In the accompanying drawings I have shown one embodiment of my invention, in which—

Figure 1 is a side elevation of an ordinary rotary fan with my improvements applied thereto. Fig. 2 is a front elevation of the apparatus constituting the different parts of my invention and with the fan and its support or motor removed. Fig. 3 is a plan view of the same. Fig. 4 is a detail in longitudinal section of the ball-bearing hanging for the supporting-frame.

Similar numbers represent like parts in all the figures.

1 is an ordinary rotary fan consisting of the central hub 2 and the vanes 3. Said hub 2 is secured to the rotary shaft 4, journaled in the casing 5, which serves as the support for the fan 1 and incloses a motor for revolving said shaft and fan.

6 is the base for sustaining the entire apparatus, including my improvements.

7 is a standard secured to the base 6 and 50 having an arm or bracket 8 extending over said base.

9 is a frame secured to the lower portion of the casing or support 5 and suspended by a ball-bearing device 10 from the bracket 8. 55 The fan-support 5, with the fan 1 and its connected parts, is thus suspended from the bracket 8 in a manner to permit its free rotation. I have shown in the drawings a very simple form of the frame 9, which consists of 60 two legs 11 11, united at the pivotal bearing 10, spreading outward and backward and terminating in the two feet 12 12, which extend under the support 5, their forward or toe ends 13 being secured to the front portion of said 65 casing. The bend of the feet 12, with the legs 11, extend around the rear of the bottom of the support 5, and the upwardly-extending toe 13 of each of said feet passes through a lug 14 on said support. 70

15 is a cross bar or brace connecting the two feet 12 under the upper pivotal bearing 10, and 16 is a pin extending upward from the base 6 and passing loosely through a hole in the bar 15. This pin 16 is preferably opposite and directly under the center of the pivotal bearing 10, and said pin acts not only as a center of rotation for the fan-casing 1 and the fan, but also as a means to prevent lateral movement of the same, which might 80 strain the pivotal connection 10.

17 is a wire guard secured to the support 5 and surrounding the fan 1 for preventing contact with the fan from outside objects.

18 19 are vertical blades or vanes loosely 85 pivoted at each end in bearings 20 at the upper and lower portions of the guard 17 in front of the wings 3 of the fan and extending at right angles with the shaft 4. A very simple construction for said bearings is to 90 make them of wire bent into loops to form the pivotal bearings of the blades and secure each end of the wire to the wire guard 17, as shown in the drawings. The blades 18 19 are also connected together back of their fulcrum or pivots by a rigid tie 21, so that the surfaces of said blades will be parallel to each other. This tie 21 is provided with project-

ing portions or hooks 22 beyond the blades, which hooks or projections overlap a part or parts of the guard, so that the longitudinal movement of the tie 21 is limited in both directions by the hooks coming in contact with the guard 17. This construction will thus limit the pivotal movement in both directions of the blades 18 19, as it is important that the blades should be prevented from turning far enough to get in the same plane, and the position of the hooks 22 is such that they will stop the movement before the blades can acquire such a position. Extending downward from the blade 18 and below the tie 20 is an arm 23, having a horizontal extension 24. Journaled loosely on a vertical bearing on the extension 24 is a wheel 25, having preferably a rim of rubber or other yielding material. The parts 23, 24, and 25 serve as means for turning the blade 18 (and through the tie 21) the blades 19 on their pivots when any of said parts meet with an obstruction during the rotation of the fan-support. The loosely-journalized roller 25 provides means for a sufficient yielding of the parts when the rim of said wheel strikes said obstruction, and thus prevents the apparatus from being jarred and injured during its operation.

26 26 are two arms pivoted to the pin 16 under the brace 15 and provided with holes near their free ends through which headed pins 27 pass. Between the pins 27 and the pivot 16 the arms are provided with upwardly-projecting pins 28, said pins being directly in the course of the wheel 25 in the rotation of the apparatus.

29 is a plate situated under the arms 26 and provided with holes 30, circumferentially arranged with relation to the pivot 16 as a center and having the same radius as the distance between said pivot and the pins 27. This construction permits the arms 26 to be turned on the pivot 16 in either direction and locked wherever desired, the heads of the pins 27 serving as a means to turn the arms, and the shank of said pins serving as a locking and releasing means by dropping them into and lifting them out of said holes. 50 In the drawings I have shown the plate 29 made in the form of a ring as being the form that will require very little material, it being only necessary to have sufficient of a plate in which to have the holes 30.

55 The pivotal bearing 10 for the frame 9 is constructed as follows:

31 is a screw-bolt passing loosely through a vertical hole in the bracket 8 and adjustably secured to said bracket, from which it is suspended by a nut 32, screwed to said bolt above the bracket.

33 and 34 are bushings screwed to the bolt 31 and provided with annular recesses 35, protected by overhanging flanges or walls 36. 65 These bushings 33 and 34 are so attached to the bolt 31 that their recesses 35 face each other.

37 is a sleeve loosely surrounding the bolt 31 and having its opposite ends loosely entering the recesses 36 of the two bushings 33 and 34, so as to permit said sleeve to freely turn on said bolt and bushings. The sleeve 37 is provided with two annular shoulders 38, between which and the inner ends of the bushings 33 34 a series of balls 39 are inclosed. 70 This construction forms an excellent ball-bearing for the sleeve 37, which is fixed to the frame 9, so that said frame will be permitted a perfectly free revolution on its suspended bearing 10.

40 is a nut screwed to the end of the bolt 31 below the bushing 34 to hold said bushing in place.

The operation is as follows: The arms 26 are first adjusted by the pins 27, so that the 85 distance between the pins 28 will be the limit of the rotary movement of the apparatus in both directions. The motor is then put into operation, causing the vanes 3 of the fan to rotate on its shaft 4. The current of air 90 caused by such revolution of the fan will strike against one side (say the right) of each of the blades 18 and 19, driving said blades and the entire apparatus in the opposite direction, (to the left.) As the apparatus can 95 move only on a pivot it turns in the direction in which it is forced. The turning of the apparatus will continue in one direction until the roller 25 strikes one of the pins or projections 28 and cause the blades 18 19 to turn on 100 their pivots, and thus present their opposite sides, (those that have not just been acted on,) to the current of air from the fan. Such current will then strike against said sides of the blades and force them and the entire apparatus to turn in the opposite direction to that it held before and until the roller 25 strikes a pin 28, when the blades will be turned again and the operation will be repeated.

From the above it will be seen that the entire apparatus can be made to automatically and continuously rotate back and forth in an arc of any desired length, the current from the fan being carried or swept around by such rotation and deflected from the sides of the 115 blades to which the air strikes, thereby causing such current to move radially through the entire arc of its course and enabling an entire compartment or any part of a compartment to be swept by such current of air. The 120 area to be swept by the currents of air may be increased or diminished at pleasure by lengthening or shortening the arc of its movement by means of the adjustable arms 26.

What I claim as new, and desire to secure 125 by Letters Patent, is—

1. In combination with a fan, a movable support for said fan, a movable blade or vane carried by said support in the path of the currents of air from the fan, and means for automatically moving said blade into a different plane at a certain point or points in the course of its movement, whereby opposite sides of said blade will be respectively pre-

sented to and struck by the currents of air from the fan, thereby causing the fan and its support to move alternately in opposite directions, and also whereby said currents of air are caused to be deflected from the sides of the blade.

2. In combination with a fan, a movable support for said fan, a movable blade or vane carried by said support in front of said fan, and means for automatically moving said blade into a different plane at a certain point or points in the course of its movement, whereby opposite sides of said blade will be respectively presented to and struck by the currents of air from the fan, thereby causing the fan and its support to move alternately in opposite directions, and also whereby said currents of air are caused to be deflected from the sides of the blade.

20 3. In combination with a fan, a pivoted support for said fan, a movable blade or vane carried by said support in the path of the currents of air from the fan, and means for automatically moving said blade into a different plane at a certain point or points in the course of its movement, whereby opposite sides of said blade will be respectively presented to and struck by the currents of air from the fan, thereby causing the fan and its support to rotate alternately in opposite directions, and also whereby said currents of air are caused to be deflected from the sides of the blade.

4. In combination with a fan, a movable support for said fan, a rotatable blade or vane carried by said support in the path of the currents of air from the fan, and means for automatically turning said blade into a different plane at a certain point or points in the course of its movement, whereby opposite sides of said blade will be respectively presented to and struck by the currents of air from the fan, thereby causing the fan and its support to move alternately in opposite directions, and also whereby said currents of air are caused to be deflected from the sides of the blade.

5. In combination with a fan, a pivoted support for said fan, a rotatable blade or vane carried by said support in the path of the currents of air from the fan, and means for automatically turning said blade into a different plane at a certain point or points in the course of its movement, whereby opposite sides of said blade will be respectively presented to and struck by the currents of air from the fan, thereby causing the fan and its support to move alternately in opposite directions, and also whereby said currents of air are caused to be deflected from the sides of the blade.

6. In combination with a fan, a movable support for said fan, a movable series of blades or vanes carried by said support in the path of the currents of air from the fan, and means for automatically moving said blades into different planes at a certain point or points in

the course of their movement, whereby opposite sides of said blades will be respectively presented to and struck by the currents of air from the fan, thereby causing the fan and its support to move alternately in opposite directions, and also whereby said currents of air are caused to be deflected from the sides of the blades.

7. In combination with a fan, a movable support for said fan, a movable series of parallel blades or vanes carried by said support in the path of the currents of air from the fan, and means for automatically moving said blades into different planes at a certain point or points in the course of their movement, whereby opposite sides of said blades will be respectively presented to and struck by the currents of air from the fan, thereby causing the fan and its support to move alternately in opposite directions, and also whereby said currents of air are caused to be deflected from the sides of the blades.

8. In combination with a fan, a movable support for said fan, a movable blade or vane carried by said support in the path of the currents of air from the fan, an arm extending from said blade, and an obstruction or obstructions situated in the course of movement of said arm for automatically moving it and said blade into a different plane, whereby opposite sides of said blade will be respectively presented to and struck by the currents of air from the fan, thereby causing the fan and its support to move alternately in opposite directions, and also whereby said currents of air are caused to be deflected from the sides of the blade.

9. In combination with a fan, a movable support for said fan, a movable series of parallel blades or vanes carried by said support in the path of the currents of air from the fan and connected by a tie having means for limiting its movement and that of the blades in either direction, and means for automatically moving said blades into different planes at a certain point or points in the course of their movement, whereby opposite sides of said blades will be respectively presented to and struck by the currents of air from the fan, thereby causing the fan and its support to move alternately in opposite directions, and also whereby said currents of air are caused to be deflected from the sides of the blades.

10. In combination with a fan, a movable support for said fan, a movable series of blades or vanes carried by said support in the path of the current of air from the fan and connected by a tie having means for limiting the rotatable movement of the blades in either direction, and means for automatically turning said blades at a certain point or points in the course of their movement, whereby opposite sides of said blades will be respectively presented to and struck by the currents of air from the fan, thereby causing the fan and its support to move alternately in opposite directions, and also whereby said currents of

- air are caused to be deflected from the sides of the blades.
11. In combination with a fan, a movable support for said fan, a movable series of blades or vanes carried by said support in the path of the currents of air from the fan, and connected by a tie, an arm extending from said blades and an obstruction or obstructions situated in the course of movement of said arm for automatically moving it the tie and blades in different planes when the arm strikes the obstruction or obstructions, whereby opposite sides of said blades will be respectively presented to and struck by the currents of air from the fan, thereby causing the fan and its support to move alternately in opposite directions, and also whereby said currents of air are caused to be deflected from the sides of the blades.
12. In combination with a fan, a movable support for said fan, a movable blade or vane carried by said support, an adjustable stop for automatically moving said blade into a different plane at a certain point or points in the course of its movement, whereby opposite sides of said blade will be respectively presented to and struck by the currents of air from the fan, thereby causing the fan and its support to move alternately in opposite directions, and also whereby said currents of air are caused to be deflected from the sides of the blade.
13. In combination with a fan, a movable support for said fan, a movable blade or vane carried by said support and provided with an extension, an adjustable stop for automatically moving said blade into a different plane when said extension strikes said stop, whereby opposite sides of said blade will be respectively presented to and struck by the currents of air from said fan, thereby causing the fan and its support to move alternately in opposite directions, and also whereby said currents of air are caused to be deflected from the sides of the blade.
14. In combination with a fan, a movable support for said fan, a movable blade or vane carried by said support in the path of the current of air from the fan, a pivotal arm provided with means for automatically moving said blade into a different plane at a certain point or points in the course of its movement, all as and for the purposes set forth.
15. In combination with a fan, a movable support for said fan, a movable blade or vane carried by said support in the path of the current of air from the fan, two pivotal arms provided with means for automatically moving said blade into a different plane at a certain point or points in the course of its movement, all as and for the purposes set forth.
16. In combination with a fan, a movable support for said fan, a movable blade or vane carried by said support in the path of the current of air from the fan, two arms having a common pivot, whereby they may be drawn together or separated from each other and provided with upward projections for automatically moving said blade into a different plane at a certain point or points in the course of its movement, all as and for the purposes set forth.
17. In combination with a fan, a movable support for said fan, a movable blade or vane carried by said support in the path of the current of air from the fan, two pivotal arms provided with means for automatically moving said blade into a different plane at a certain point or points in the course of its movement and said arms having means for adjusting and locking them anywhere in the course of their movement, all as and for the purposes set forth.
18. In combination with a fan, a movable support for said fan, a movable blade or vane carried by said support in the path of the current of air from the fan, and means for automatically moving said blade or vane into a different plane at a certain point or points in the course of its movement, and means for limiting the course of said movement of the blade, all as and for the purposes set forth.
19. In combination with a fan, a movable support for said fan, a series of blades or vanes carried by said support in the path of the current of air from the fan, and connected by a tie having means for limiting its movement and that of the blades in either direction, means for automatically moving said blades into different planes at a certain point or points in the course of their movement, all as and for the purposes set forth.
20. In combination with a fan, a movable support for said fan, a blade or vane fulcrumed to an extension of said fan-support, and in front of said fan, and means for automatically moving said blade into a different plane at a certain point or points in the course of its movement, whereby opposite sides of said blades will be respectively presented to and struck by the currents of air from the fan, thereby causing the fan and its support to move alternately in opposite directions, and also whereby said currents of air are caused to be deflected from the sides of the blades.
21. In combination with the support for a fan, a frame pivotally suspended so as to permit free horizontal rotation, and said frame sustaining said support, and a pin situated opposite and in the same line as the pivot of said support and loosely entering a hole in the same, all as and for the purposes set forth.
22. In combination with a fan, a movable support for said fan, a movable blade or vane carried by said support, the arm 23, 24 extending from said blade, a wheel loosely pivoted to the part 24, and an obstruction or obstructions situated in the course of movement of said wheel, for automatically moving it, the arm and blade into a different plane when said wheel strikes the obstruction or obstructions, whereby opposite sides of said blades will be respectively presented to and struck by the currents of air from the fan, thereby

causing the fan and its support to move alternately in opposite directions, and also whereby said currents of air are caused to be deflected from the sides of the blades.

- 5 23. In combination with a fan, a movable support for said fan, a movable blade or vane carried by said support, a pivotal arm having a pin extending from the same, and the support for said arm having a series of holes
 10 in which the pin is adapted to engage, whereby the position of said arm may be adjusted, and means on said arm for moving said blade into a different plane at a certain point or points in the course of its movement, whereby
 15 opposite sides of said blades will be respectively presented to and struck by the currents of air from the fan, thereby causing the fan and its support to move alternately in opposite directions, and also whereby said currents of air are caused to be deflected from the sides of the blades.

- 20 24. In combination with a fan, a movable support for said fan, a movable blade or vane carried by said support, two pivotal arms
 25 each having a pin extending from the same and the support for said arms having a series of holes in which said pins are adapted to engage, whereby the position of said arms may be adjusted, and means on said arms for moving said blade into a different plane at a certain point or points in the course of its movement, whereby opposite sides of said blade will be respectively presented to and struck by the currents of air from the fan, thereby causing the fan and its support to rotate alternately in opposite directions, and also whereby said currents of air are caused to be deflected from the sides of the blade.

- 30 25. In combination with a fan, a movable support for said fan, a movable blade or vane carried by said support, a pivotal arm hav-

ing a pin loosely passing through a hole in said arm and extending from the same, and the support for said arm having a series of holes in which the pin is adapted to engage, 45 whereby the position on said arm may be adjusted, and means on said arm for moving said blade into different planes at a certain point or points in the course of its movement, whereby opposite sides of said blade will be respectively presented to and struck by the currents of air from the fan, thereby causing the fan and its support to rotate alternately in opposite directions, and also whereby said currents of air are caused to be deflected from 50 the sides of the blade. 55

26. In combination with a fan, a movable support for said fan, a movable blade or vane carried by said support, two pivotal arms each having a pin loosely passing through a 60 hole in said arm and extending from the same, and a support for said arms having a series of holes in which said pins are adapted to engage, whereby the position of said arms may be adjusted, and means on said arm for moving said blade into different planes at a certain point or points in the course of its movement, whereby opposite sides of said blade will be respectively presented to and struck by the currents of air from the fan, thereby 65 causing the fan and its support to rotate alternately in opposite directions, and also whereby said currents of air are caused to be deflected from the sides of the blade. 70

In testimony whereof I have signed my 75 name to this specification in the presence of two subscribing witnesses.

T. ROMER WEYANT.
